C. W. PUTT

CLEANING DEVICE

Filed July 22, 1921

C.W. Putt, Inventor

By Cadwalader.

Attorney

UNITED STATES PATENT OFFICE.

CHARLES W. PUTT, OF JEROME, ARIZONA.

CLEANING DEVICE.

Application filed July 22, 1921. Serial No. 436,752.

To all whom it may concern:

Be it known that I, CHARLES W. PUTT, a citizen of the United States, residing at Jerome, in the county of Yavapai and State 5 of Arizona, have invented a new and useful Cleaning Device, of which the following is a specification.

This invention relates to a mixing device such as used in preparing beverages at soda 10 fountains and the like, and to a means for use in connection therewith whereby the mixing device can be quickly and thoroughly cleaned after each mixing operation.

Heretofore it has been the practice to use 15 a rotating spindle with a small disk-like terminal which has been rotated at a high speed within a container holding the beverage. No means has been provided for cleaning this device after each successive operation and, consequently, there has been 20 danger of contamination of the prepared beverages.

One of the objects of the present invention is to provide a cleaning means set up 25 permanently in a fixed position relative to the mixing device whereby, after each successive operation of the mixing device it can be lowered into the cleaner, such action resulting in the operation of a valve whereby 30 a cleansing fluid is directed onto the stem of the mixer and is drained therefrom.

With the foregoing and other objects in view which will appear as the description proceeds, the invention resides in the combination and arrangement of parts and in the details of construction hereinafter described 35 and claimed, it being understood that, within the scope of what is claimed, changes in the precise embodiment of the invention 40 shown can be made without departing from the spirit of the invention.

The accompanying drawing represents the preferred form of the invention partly in elevation and partly in section showing the 45 mixing device in position within the cleaning apparatus.

Referring to the drawing by characters of reference 1 designates the base of the mixing device, the same being attached to a counter C or other supporting structure. Extending upwardly from this base is a tubular housing 2 having an annular flange or collar 3 at its upper end. A guide stem 4 projects upwardly from the base and is concentric with the housing and slidably mounted within the housing is a cylindrical stem 5

having an elongated recess 6 into which the stem 4 projects. A coiled spring 7 is arranged within the stem 5 and around the stem 4 and bears at one end against the base 1 and at its other end against the upper wall of the recess 6. This spring thus serves to hold the stem 5 normally raised within the housing 2. In order to hold the stem 5 in its lowermost position with the spring 7 under compression, a latch 8 is pivotally connected to the upper portion of the stem 5 and is adapted, when said stem is thrust downwardly, to engage the collar 3 as shown in the drawing.

An elongated head 9 is provided at the upper end of the stem 5 and forms a hand rest and extending from this head is a projecting portion 10 to which is secured the housing 11 of an electric motor. A spindle 12 extends downwardly from the housing and is adapted to be driven by the motor, this spindle being provided at its lower end with a small disk 13.

The structure thus far described is that used for mixing beverages placed in glasses or other containers, the spindle 12 being inserted downwardly into the beverage and then rotated by the motor. For the purpose of cleaning the spindle after it has been raised from the mixed beverage, there is mounted on the supporting structure C at a proper point, a housing 14 divided by a transverse partition 15 into a lower water compartment 16 and an upper cleaning compartment 17. Supported within the cleaning compartment is an inner casing 18 having a plurality of apertures communicating with the space therearound and thereunder and extending from the bottom of this inner casing is a drain pipe 19. An inlet opening 20 is formed in the partition 15 and is normally closed by a valve 21 having a stem 22 extending downwardly therefrom into a removable screw plug 23. A spring 24 serves to hold this valve normally upon its seat so as to close the opening 20. A stem 25 projects from the valve 21 through the opening 20 and through an opening in the bottom of the inner casing 18 where it will be contacted by the disk 13 when lowered into the inner casing.

The inner casing 18 is adapted to be inserted downwardly into the housing 14 through a threaded opening 26 in the top of the housing and screwed into this opening is a retaining ring 27 having a down-

wardly tapered opening 28 provided with a rubber gasket 29 or the like constituting a lining.

Normally the valve 21 is shut. After the 5 spindle 12 has been used for mixing a beverage the stem 5 can be rotated so as to position the spindle above the opening in the top of the housing 14. The spindle can then be moved downwardly so as to cause the 10 lower portion of the motor housing 11 to engage the gasket 29 and close the top of the housing. At the same time the latch 8 will engage collar 3 and hold the parts in their lowered positions and the disk 13 will 15 come against the stem 25 and open valve 21. This water supplied to the compartment 16 through an inlet pipe 30 will flow upwardly into the space between the housing 14 and the inner casing 18 and will be 20 delivered in small jets through the openings 31 in the inner casing and thus thoroughly clean the spindle 12 and the disk 13. The water will drain outwardly through the pipe 19 and the cleaning operation will 25 continue as long as the parts are held in their lowered positions. By releasing the latch 8 the spring 7 will automatically raise stem 5 and motor casing 11 whereupon the valve 21 will automatically close.

30 What is claimed is:—

1. The combination with a motor having a tapered neck of a cleaning device for 35 cleaning an article rotated by said motor comprising an imperforate housing having a closed lower end and an open upper end, a retaining ring removably mounted in the open end of said housing with its inner face

beveled to form a seat for said motor neck, a perforated inner casing mounted in said housing beneath said retaining ring and 40 spaced from the side walls of the housing, and means operable by contact with the article being cleaned in the casing to admit fluid under pressure into the space between the housing and the casing whereby it is 45 forced out in jets through the perforations in the casing against the article to be cleaned.

2. A cleaning device of the class described comprising an imperforate housing having 50 an open upper end equipped with a retaining ring, a perforated casing mounted in the housing beneath said ring, said housing having a transverse partition near its lower end with an opening in said partition, a spring 55 pressed valve to normally close the opening in the partition and having a stem extending through said opening and loosely through the bottom of the casing to position it for engagement by an article to be 60 cleaned to open the valve against the tension of its spring, the bottom of said housing having a fluid inlet opening there-through beneath said partition, and a drain pipe opening through the bottom of the 65 casing.

In testimony that I claim the foregoing as my own, I have hereto affixed my signature in the presence of two witnesses.

CHARLES W. PUTT.
